FABRIC DRAWING-OFF MECHANISM FOR
KNITTING MACHINESThomas Charles Bromley and Arthur Shortland,
Leicester, EnglandApplication December 2, 1940, Serial No. 368,266
In Great Britain November 8, 1939

15 Claims. (Cl. 66—153)

Fabric drawing-off mechanisms are employed in knitting machines for the purpose of putting tension on the knitted fabric to facilitate casting of knitted loops off the needles, and pulling the fabric away from the needles.

The present invention relates to fabric drawing-off mechanism of the form employed, more particularly, in circular knitting machines and comprising a pair of rollers between which the fabric is gripped and by appropriate rotation of which the requisite pull is exerted on the fabric. Mechanism of this character may be used alone in which case the fabric leaving the rollers may be accumulated in a fabric can, or it may be used in conjunction with a separately controlled mechanism whereby the fabric is wound up after leaving the rollers.

In mechanism of this form one or each of the rollers is carried by bearings fitted slidably in slots or guides in a bracket or like carrier, and the roller or each roller is pressed towards the other, e. g. by spring means, in order to maintain the grip on the fabric which passes between the said rollers. Heretofore the rollers have been geared together at one or each end and one roller has been driven by cam actuated pawl and ratchet mechanism or through the medium of worm or equivalent gearing, suitably driven.

It frequently happens with drawing-off mechanism of this particular form that due to varying thickness of the fabric such as is occasioned by the presence of pouches or like formations at intervals, as for example heel and toe pouches in seamless hosiery, the rollers are forced apart to such an extent as to put them partly or wholly out of gear so that they either function imperfectly or fail to function for the intended purpose.

The present invention comprises an improved drawing-off mechanism of the form concerned the object of which is to obviate the aforesaid disadvantage.

According to this invention the rollers of the drawing-off mechanism are not geared together but are entirely separate and driven independently so that in the event of them being forced apart abnormally the rollers are still driven and continue to function normally.

By the expression "driven independently" is meant that the rollers are both actually driven by the driving means, in contra-distinction to an arrangement wherein one only of the rollers is so driven and arranged to transmit the drive to the other roller through the medium of gearing. That is to say, in the improved mechanism

neither of the rollers depends for its motion upon the other but both rollers are driven directly by or from the driving means. In this connection, however, the driving means may be common to both rollers and include a common driving part or member, or the rollers may be driven by respectively different independently operated driving parts or members.

In conjunction with the improved roller driving means there may be provided means whereby the rate at which the gripping rollers are driven can be varied infinitesimally within predetermined limits according to the rate at which fabric is to be produced, and/or the quality, as regards stiffness or slackness, to be produced, the said last mentioned means being, for example, of the general character described in the specification of our prior United States Letters Patent No. 1,956,638.

Specific constructional forms of the improved fabric drawing-off mechanism applicable to a circular hosiery machine of the rotary cylinder type will now be described, by way of example.

In the accompanying purely diagrammatic drawings,

Figure 1 is a plan view of one form of such mechanism,

Figure 2 is a part sectional end view of the same as seen in the direction of the arrow A in Figure 1, showing the ends of the fabric gripping rollers and ratchet mechanism for operating the same,

Figure 3 is a longitudinal sectional view of said mechanism, partly in outside elevation, taken on the line III—III of Figure 2,

Figures 4 and 5 are views similar to Figures 2 and 3 respectively illustrating a modified form of ratchet mechanism,

Figure 6 is a plan view of the improved drawing-off mechanism modified to include means for varying the rate at which the rollers are driven as hereinbefore alluded to, and

Figure 7 is an end view thereof—partly in section.

Like parts are designated by similar reference characters throughout the drawings.

For the information of the reader it ought to be explained that none of the figures of the drawings are intended to be complete in so far as only such parts are shown as are necessary for a clear understanding of the constructions concerned.

The drawing-off mechanism shown in Figures 1-3 comprises two fabric gripping rollers 1 and 2 which are rotatably mounted side by side in a

pair of oppositely formed upstanding brackets 3 and 4. These brackets constitute bearings for the rollers and are carried by a gear wheel 5 which latter is mounted to rotate upon a stationary support 6. End caps 7 and 8 are applied to the brackets 3 and 4 respectively and, as shown in Figure 2, are secured in position by means of screws 9. The mechanism revolves bodily in unison with the needle cylinder or cylinders of the circular hosiery machine to which said mechanism is applied. In this connection the gear wheel 5 is arranged to mesh with a pinion 10 which is in turn adapted to be driven from the main shaft of the machine (not shown). The pinion 10 is secured to a shaft 11 the lower end 10 of which is rotatably mounted in a bearing 12 formed in the support 6. The said support is, of course, rigidly secured to the frame of the machine. The gear wheel 5 has formed therein a central hole or opening 5a through which the fabric passes as it is drawn off from the needles. With the exception of their end portions—which are plain—the rollers 1 and 2 are longitudinally fluted, grooved or otherwise formed in any suitable conventional manner to enhance the gripping effect thereof. The plain end portions of the roller 1 are fitted in circular holes in the brackets 3 and 4, whereas the corresponding portions of the companion roller 2 project into and are supported within elongated openings 13 in said brackets (see Figure 2). Irrespective of rotary movement the roller 2 is therefore enabled to move bodily in relation to the roller 1 suchwise as to permit of appreciable separation of the rollers to allow for differences in the thickness of the fabric produced on the machine. Normally the rollers are pressed firmly together by means of two spring-influenced levers 14 which are disposed one at each end of the movable roller 2 and pivotally mounted as indicated at 15 within appropriately recessed or slotted portions of the bearing end caps 7 and 8. Each lever 14 is controlled by a tension spring 16 and is furnished at its inner side with a small presser roller 17 arranged to act upon the adjacent plain end portion of the roller 2 for the purpose of urging the latter up to the companion roller 1. The brackets 3 and 4 are slotted at 18 to receive the presser rollers 17 and also to permit of required movements of the levers 14, that is to say against the spring action upon separation of the fabric gripping rollers and vice versa. The springs 16 are accommodated within longitudinal grooves 19 formed in the bearing end caps 7 and 8, one end of each spring being connected to the upper extremity of the corresponding lever 14 while the opposite end is anchored to a fixed hook 20. By reason of this construction the roller 2 is yieldably mounted.

It will be noted that the gripping rollers 1 and 2 are entirely separate in so far as they are not geared together. Furthermore, in accordance with the essential feature of the present invention, the two rollers are driven independently in the manner and by the means now to be described.

The extreme ends of each fabric gripping roller are formed with ratchet teeth 21. That is to say, there is a similar circular series of such teeth at each end of each roller. The form of the teeth is shown more clearly at the left-hand side of Figure 3, wherein it will be seen that said teeth are cut in an axial direction as distinct from being formed or applied circumferentially. A pawl 22 mounted upon a cam actuated and spring 75

(or equivalently) controlled slide 23 is provided at each end of the mechanism for co-operation with the ratchet teeth 21 at that end. The pawls are common to both rollers in which respect it will be observed that each pawl is disposed substantially centrally between the rollers and has an operative extremity 22a of such width as to extend over one tooth on each roller. This width is indicated at B in Figure 2 and is sufficient to maintain each pawl in engagement with the appropriate ratchet teeth even in the event of the rollers 1 and 2 being separated to an abnormal extent. By effecting reciprocation of one of the pawls 22 the rollers will be simultaneously racked around in opposite directions, i. e. in the directions indicated by the arrows C in Figure 2. The arrangement is such, however, that while one of the pawls is making an operative stroke the other is on the return or idle stroke, as will be hereinafter more fully described, so that the gripping rollers are never allowed to rest, i. e. they are driven practically continuously—when the machine is working. The body portion of each pawl 22 is accommodated within a bifurcated or forked portion 23a of the corresponding slide 23 and is mounted so as to be capable of turning about a pivot pin 24 carried by the said slide. The pawl is yieldingly held in contact with the teeth 21 and thereby controlled by a spring 25 appropriately arranged. The slide 23 is mounted for movement vertically within a groove 26 formed in the bearing end cap. The opposite sides of this groove afford lateral guidance for the slide. At its lower end the slide 23 is provided with a cam roll 27 arranged for contact with the upper edge of a circular flanged portion 6a of the support 6. This flanged portion is appropriately formed with a rise so as to constitute a cam ring which is presented to the roll 27 during bodily rotation of the drawing-off mechanism. A compression spring 28 is employed to control the slide 23. This spring is vertically disposed and arranged in the manner depicted between the top of a suitably recessed portion of the bearing end cap and an extension 23b at the foot of the slide. Pins or pegs 29 and 30 constrain the spring 28 to maintain its correct position axially. The bearing end cap is recessed at its lower end in the region of the cam roll 27, as indicated at 31, to permit of required movements of the slide. The construction is consequently such that during each revolution of the mechanism, the cam roll 27 is acted upon by the aforesaid cam ring to effect an upward movement of the slide 23 against the action of the spring 28 and thereby impart an idle stroke to the pawl 22 which latter thereupon first yields outwardly and then snaps back into driving engagement with the appropriate ratchet teeth. Immediately thereafter the cam roll 27 will ride down the rise on the cam ring and accordingly permit the slide to move down again under the reaction of the spring 28, thereby imparting an operative stroke to the pawl 22 and driving both gripping rollers simultaneously. A complete reciprocation of the slide and hence also rotation of the rollers 1 and 2 to the extent of one step will therefore be effected once per complete revolution of the mechanism. As will be understood, the pawl and ratchet mechanism at each end of the rollers is of precisely similar construction but since these duplicate sets of mechanism operate alternately with each other, then the rollers will, of course, be continuously driven, as already alluded to. It will be appreciated that

in this example spring action is relied on to impart operative strokes to the pawls 22.

The construction illustrated in Figures 4 and 5 is in many respects similar to that last described, but differs in two important particulars, viz, in that pawl and ratchet mechanism is provided at one end only of the gripping rollers 1 and 2 so that the latter are intermittently rotated instead of being continuously driven, and in that the operative strokes of the pawl or clawker are effected in a positive manner by cam action, said pawl or clawker being merely returned by spring means.

Here again, the extreme ends of each fabric gripping roller are formed with axially extending ratchet teeth 21', the teeth at one end of the mechanism co-operating with a cam-operated clawker 32, common to both rollers, while those at the opposite end are adapted for co-operation with suitably spring-influenced back stop pawls or detents 33 (Figure 5). In this case, however, the pitch of the ratchet teeth 21' is twice that of the teeth 21 in the first described example. This, of course, is to ensure that the gripping rollers although intermittently actuated shall be driven at the same rate as the continuously driven rollers. The clawker 32 is loosely mounted between guides or in a groove formed on or in the end cap 7 of the bracket 3 suchwise as to be capable not only of sliding up and down, but also of pivoting or canting forwards and backwards about the point 34 (see Figure 5). The clawker, moreover, is disposed more or less centrally between the rollers 1 and 2 and has at its upper end a laterally spread operative extremity 32a of such width as to extend well over one ratchet tooth 21' on each roller even in the event of the rollers being separated abnormally. A tension spring 35, provided to control the clawker, is accommodated within a groove 36 formed in the end cap 7 and is anchored at one end to a peg 37 which is screwed into the said cap and at the other end to a projection 38 on the clawker. This spring functions not only to impart idle or return strokes to the clawker at appropriate times but also serves normally to tilt the latter forwards to urge its upper operative extremity 32a into engagement with the ratchet teeth. At its lower end the clawker is formed with a protuberant foot portion 32b upon which rests one end of a cam-actuated lever 39. This lever is pivoted at 40 upon the outside of the bearing bracket 3 and the end 39a of said lever resting upon the foot portion 32b is conveniently of suitably rounded or bulbous formation as shown in Figure 4. The opposite end of the lever 39 is furnished with a cam roll 41 arranged for contact with the upper edge of the aforesaid circular cam ring constituted by the flange 6a. The arrangement is therefore such that at each revolution of the drawing-off mechanism, the cam roll 41 is acted upon by the rise on the cam ring, whereupon the lever 39 is turned about its pivot 40 so that its rounded or bulbous end 39a presses downwardly upon the foot portion 32a to effect depression of the clawker 32 against the action of the spring 35. In this way the clawker makes an operative stroke, thereby pulling round the rollers 1 and 2 simultaneously in opposite directions to the extent of one step, immediately after which the back stop pawls or detents 33 snap into position to hold the rollers in position preparatory to being racked round again at the next operative stroke of the clawker. Meanwhile, the

cam roll 41 rides down the rise on the cam ring and thereby permits the clawker to be pulled up again under the action of the tension spring 35. During its return or idle stroke the said clawker first pivots or canters backwards and thereafter snaps back into driving engagement with the appropriate ratchet teeth under the control of the spring 35.

Figures 6 and 7 show means whereby the rate at which the rollers 1 and 2 are driven can be varied. The said means, which are suitable for use in conjunction with either of the forms of driving mechanism herein specifically disclosed, include a ring 42 (or equivalent) which is carried pivotally by fixed brackets 43 attached to the support 6. In this connection the ring is bossed at each side as indicated at 42a for reception of a pivot pin 44 as shown more clearly in Figure 6. The ring 42, moreover, constitutes a race and has a flat upper side 42b upon which the aforementioned cam rolls 27 or 41 (as the case may be) are supported. In this respect, therefore, the ring 42 takes the place of the flanged portion 6a of the support 6 in the two previous examples. The ring 42 is adjustable, as indicated in dot-and-dash lines in Figure 7. It will be understood that when said ring is in the horizontal, i. e. zero, position represented in the dot-and-dash lines no vertical component of movement will be imparted to the cam rolls when the drawing-off mechanism is revolved bodily; consequently the pawl and ratchet gearing will remain quiescent with the result that the gripping rollers 1 and 2 will not be driven. When, however, the ring 42 is inclined, e. g. adjusted to the position represented by full lines in Figure 7, the pawl and ratchet gearing will be operated to drive the gripping rollers in the manner required. Since the ring 42 is adjustable to any inclination within a certain desired range, the rate at which the rollers 1 and 2 are driven and consequently the feed imparted to the fabric per revolution of the machine can be varied between desired limits. The cam ring 42 may be adjustable either automatically or by hand to effect the required variation in speed. For example, in a knitting machine wherein provision is made for automatically adjusting the stitch cam or cams to stiffen or slacken the fabric, variation in the speed of the drawing-off mechanism may be effected automatically with the adjustment of the stitch cam or cams, e. g. by connections from the existing controlling mechanism of the machine. This is the intention with the arrangement depicted in Figures 6 and 7 wherein it will be seen that the ring 42 is formed with spaced apertured lugs 45 between which can be connected a rod or link (not shown) forming part of connections from such controlling mechanism. When hand operable or equivalent means are provided for effecting adjustment of the ring 42, such adjustments may be made at the will and discretion of the operative in charge of the machine.

Ratchet mechanism such as that described with reference to Figures 1-3 may, if desired, be provided at one end only of the gripping rollers 1 and 2 for imparting intermittent instead of continuous motion to the latter during the production of fabric. Again, duplicate sets of ratchet mechanism similar to that shown in Figures 4 and 5 may be arranged respectively at opposite ends of the rollers and adapted to be operated alternately with each other so as to impart continuous motion to said rollers. That is to say,

irrespective as to whether the gripping rollers are to have continuous or intermittent motion imparted to them, either of the forms of ratchet mechanism herein specifically described—suitably arranged—may be adopted.

The present invention is applicable primarily to fabric drawing-off mechanism for circular hosiery knitting machines of the latch or bearded needle type, plain or rib, in which the said mechanism revolves bodily in the case of a machine of the rotary cylinder type, and remains stationary while the rollers are rotated in the case of a machine of the stationary cylinder type, the actuating cam remaining stationary or revolving accordingly.

The invention is not to be regarded as limited to hosiery knitting machines as it may be applied to fabric drawing-off mechanism of machines of larger sizes and, if desired, flat and like knitting machines by suitable adaptation of the roller operating means.

It will be understood that an independent drive, such for example as pawl and ratchet mechanism of the character last described, may be provided at each end of each of the rollers for the purpose of equalizing the pressure on the rollers when the latter are being driven or racked round.

In any event, if for any reason the thickness of the fabric to be dealt with by the drawing-off mechanism varies, one or each of the rollers, according to whether one or each is yieldably mounted, will adapt itself to the varying conditions without adversely affecting the driving of the mechanism.

What we claim then is:

1. Mechanism for drawing-off fabric as it is produced on a knitting machine, comprising, in combination, a pair of rollers between which fabric is gripped and at least one of which is yieldably mounted so that said rollers are normally pressed together but permitted to separate as and when required, said rollers being entirely separate in contra-distinction to being geared together, and each roller being provided at each end with ratchet teeth, a feed pawl which is formed and arranged for co-operation with the ratchet teeth of both rollers at one end of the latter, another feed pawl which is similarly formed and arranged for co-operation with the ratchet teeth of both rollers at the opposite end thereof, and means for operating said feed pawls whereby the rollers are driven independently in opposite directions and continue to function normally even in the event of them being forced apart abnormally.

2. Mechanism for drawing-off fabric as it is produced on a knitting machine, comprising, in combination, a pair of rollers between which fabric is gripped and at least one of which is yieldably mounted so that said rollers are normally pressed together but permitted to separate as and when required, said rollers being entirely separate in contra-distinction to being geared together, and each roller being provided at each end with ratchet teeth, a feed pawl which is formed and arranged for co-operation with the ratchet teeth of both rollers at one end of the latter, another feed pawl which is similarly formed and arranged for co-operation with the ratchet teeth of both rollers at the opposite end thereof, and means for operating said feed pawls alternately with each other whereby the rollers are driven independently during the production of fabric and continue to function normally even

in the event of them being forced apart abnormally.

3. Mechanism for drawing-off fabric as it is produced on a knitting machine, comprising, in combination, a pair of rollers between which fabric is gripped and at least one of which is yieldably mounted so that said rollers are normally pressed together but permitted to separate as and when required, said rollers being entirely separate in contra-distinction to being geared together and each roller being provided at each end with ratchet teeth, a clawker which is formed and arranged for co-operation with the ratchet teeth of both rollers at one end of the latter, means for operating said clawker whereby the rollers are driven independently in an intermittent manner during the production of fabric and continue to function normally even in the event of them being forced apart abnormally, and a back stop pawl for co-operation with the ratchet teeth at the end of the rollers remote from the clawker to prevent backward rotation of said rollers.

4. Mechanism for drawing-off fabric as it is produced on a knitting machine, comprising, in combination, a pair of rollers between which fabric is gripped and at least one of which is yieldably mounted so that said rollers are normally pressed together but permitted to separate as and when required, said rollers being entirely separate in contra-distinction to being geared together and each roller being provided at each end with ratchet teeth, a feed pawl which is formed and arranged to operate with a pulling action upon the ratchet teeth of both rollers at one end of the latter, another feed pawl which is similarly formed and arranged to operate with a pulling action upon the ratchet teeth of both rollers at the opposite end thereof and means for actuating said feed pawls alternately with each other whereby the rollers are simultaneously and independently rotated in opposite directions during the production of fabric and continue to function normally even in the event of them being forced apart abnormally.

5. Fabric drawing-off mechanism according to claim 3, wherein the clawker acts upon the appropriate ratchet teeth with a pulling action.

6. Mechanism for drawing-off fabric as it is produced on a knitting machine, comprising, in combination, a pair of rollers between which fabric is gripped and at least one of which is yieldably mounted so that said rollers are normally pressed together but permitted to separate as and when required, said rollers being entirely separate in contra-distinction to being geared together and each roller being provided at each end with ratchet teeth, a spring-influenced feed pawl which is formed and arranged for co-operation with the ratchet teeth of both rollers at one end of the latter, spring means arranged to effect the operative strokes of said feed pawl at appropriate times, another spring-influenced feed pawl which is similarly formed and arranged for co-operation with the ratchet teeth of both rollers at the opposite end thereof, further spring means arranged to effect the operative strokes of the last mentioned feed pawl, and cam means for imparting the idle strokes to the feed pawls alternately with each other against the action of the associated spring means, the arrangement being such that the gripping rollers are simultaneously driven independently in opposite directions during the production of fabric and continue to function nor-

mally even in the event of them being forced apart abnormally.

7. Mechanism for drawing-off fabric as it is produced on a knitting machine, comprising, in combination, a pair of rollers between which fabric is gripped and at least one of which is yieldably mounted so that said rollers are normally pressed together but permitted to separate as and when required, said rollers being entirely separate in contra-distinction to being geared together and each roller being provided at each end with ratchet teeth, a clawker which is so formed and arranged for canting movement backwards and forwards as to enable it to co-operate with the ratchet teeth of both rollers at one end of the latter, spring means for controlling said clawker and effecting the idle strokes of the latter at appropriate times, cam-actuated means for imparting the operative strokes to the clawker against the action of said spring means, the arrangement being such that the gripping rollers are driven independently in an intermittent manner during the production of fabric and continue to function normally even in the event of them being forced apart abnormally, and a back stop pawl for co-operation with the ratchet teeth at the end of the rollers remote from the clawker to prevent backward rotation of said rollers.

8. Mechanism for drawing-off fabric as it is produced on a knitting machine, comprising, in combination, a pair of rollers between which fabric is gripped and at least one of which is yieldably mounted so that said rollers are normally pressed together but permitted to separate as and when required, said rollers being entirely separate in contra-distinction to being geared together and each roller being provided at each end with ratchet teeth which extend in an axial direction with respect to the rollers, a feed pawl which is arranged for co-operation with the ratchet teeth of both rollers at one end of the latter, the operative extremity of said pawl being of such width as to be capable of engaging one tooth on each roller even in the event of the rollers being forced apart abnormally, another feed pawl which is similarly formed and arranged for co-operation with the ratchet teeth of both rollers at the opposite end thereof, and means for operating said feed pawls alternately with each other so that the rollers are independently rotated simultaneously in opposite directions during the production of fabric and continue to function normally even in the event of being forced apart abnormally as aforesaid.

9. Mechanism for drawing-off fabric as it is produced on a knitting machine, comprising, in combination, a pair of rollers between which fabric is gripped and at least one of which is yieldably mounted so that said rollers are normally pressed together but permitted to separate as and when required, said rollers being entirely separate in contra-distinction to being geared together and each roller being provided at each end with ratchet teeth which extend in an axial direction with respect to the rollers, a clawker which is arranged for co-operation with the ratchet teeth of both rollers at one end of the latter, the operative extremity of said clawker being of such width as to be capable of engaging one tooth on each roller even in the event of the rollers being forced apart abnormally, means for actuating the clawker so that the gripping rollers are independently rotated in opposite directions step by step during the production of fabric and

continue to function normally even in the event of being forced apart abnormally as aforesaid, and a back stop pawl for co-operation with the ratchet teeth at the end of the rollers remote from the clawker to prevent backward rotation of said rollers.

10. Mechanism for drawing-off fabric as it is produced on a knitting machine, comprising, in combination, a roller, roller supporting brackets having therein fixed bearings in which said roller is mounted, a companion roller which is yieldably mounted in said brackets, the two rollers being thereby adapted to grip the fabric between them and being normally pressed together but permitted to separate as and when required, the rollers also being entirely separate in contra-distinction to being geared together but each roller having at each end thereof ratchet teeth which extend in an axial direction with respect to said rollers, two pivoted spring-influenced feed pawls which are formed and arranged for co-operation with the ratchet teeth of both rollers at respectively opposite ends of the latter, slideable parts which are associated with the roller supporting brackets and serve to carry the feed pawls, springs for controlling said slideable parts, and cam means for imparting movement to said slideable parts and hence also to the feed pawls in one direction against the action of the springs at appropriate times, movement of said parts and pawls in the reverse direction being effected by the springs, the construction and arrangement being such that the gripping rollers are independently driven simultaneously in opposite directions during the production of fabric and continue to function normally even in the event of them being forced apart abnormally.

11. Mechanism for drawing-off fabric as it is produced on a knitting machine, comprising, in combination, a roller, roller supporting brackets having therein fixed bearings in which said roller is mounted, a companion roller which is yieldably mounted in said brackets, the two rollers being thereby adapted to grip the fabric between them and being normally pressed together but permitted to separate as and when required, the rollers also being entirely separate in contra-distinction to being geared together but each roller having at each end thereof ratchet teeth which extend in an axial direction with respect to said rollers, a part which is attached to the roller supporting bracket at one end of the rollers, a clawker which is mounted to slide and be capable of canting movement backwards and forwards within said part, said clawker being formed for co-operation with the ratchet teeth of both rollers at the aforesaid end, a spring for controlling the clawker, a lever arranged for action upon said clawker, cam means for actuating said lever suchwise as to impart movement to the clawker in one direction at appropriate times against the action of the controlling spring, movement of the clawker in the reverse direction being effected by said spring and the construction being such that the gripping rollers are driven independently in an intermittent manner during the production of fabric and continue to function normally even in the event of them being forced apart abnormally, and elements for co-operation with the ratchet teeth at the end of the rollers remote from the clawker to prevent backward rotation of said rollers.

12. Mechanism for drawing-off fabric as it is produced on a knitting machine, comprising in combination, a pair of separate rollers between

which fabric is gripped and at least one of which is yieldably mounted so that said rollers are normally pressed together but permitted to separate as and when required, each roller being provided at at least one end with ratchet teeth, a pawl which is common to both rollers and arranged for cooperation with the ratchet teeth at the said end of the rollers, the operative end of said pawl being of such formation as to be capable of engaging one tooth on each roller even in the event of the rollers being forced apart abnormally, and means for operating said pawl so that the rollers are independently rotated simultaneously in opposite directions during the production of fabric and continue to function normally even when forced apart as aforesaid.

13. Mechanism for drawing-off fabric as it is produced on a knitting machine, comprising, in combination, a pair of separate rollers between which fabric is gripped and at least one of which is yieldably mounted so that said rollers are normally pressed together but permitted to separate as and when required, each roller being provided at at least one end with ratchet teeth, a pawl which is common to both rollers and arranged for cooperation with the ratchet teeth at the said end of the rollers, the operative end of said pawl being of such formation as to be capable of engaging one tooth on each roller even in the event of the rollers being forced apart abnormally, means for operating said pawl so that the rollers are independently rotated simultaneously in opposite directions during the production of fabric and continue to function normally even when forced apart as aforesaid, and means whereby the rate at which the gripping rollers are driven can be varied within predetermined limits, for the purposes herein specified.

14. Mechanism for drawing-off fabric as it is produced on a knitting machine, comprising, in combination, a pair of separate rollers between which fabric is gripped and at least one of which is yieldably mounted so that said rollers are normally pressed together but permitted to separate as and when required, each roller being pro-

vided at at least one end with ratchet teeth, a pawl which is common to both rollers and arranged for cooperation with the ratchet teeth at the said end of the rollers, the operative end of said pawl being of such formation as to be capable of engaging one tooth on each roller even in the event of the rollers being forced apart abnormally, means for operating said pawl so that the rollers are independently rotated simultaneously in opposite directions during the production of fabric and continue to function normally even when forced apart as aforesaid, a cam ring for effecting actuation of said ratchet gearing, and means whereby said cam ring can be adjusted to any desired extent between a zero position and a predetermined maximum position so that the rate at which the rollers are driven can be varied within limits, for the purposes herein specified.

15. Mechanism for drawing-off fabric as it is produced on a knitting machine, comprising, in combination a pair of separate rollers between which fabric is gripped and at least one of which is yieldably mounted so that said rollers are normally pressed together but permitted to separate as and when required, each roller being provided at at least one end with ratchet teeth, a pawl which is common to both rollers and arranged for cooperation with the ratchet teeth at the said end of the rollers, the operative end of said pawl being of such formation as to be capable of engaging one tooth on each roller even in the event of the rollers being forced apart abnormally, means for operating said pawl so that the rollers are independently rotated simultaneously in opposite directions during the production of fabric and continue to function normally even when forced apart as aforesaid, and a cam ring for effecting actuation of said ratchet gearing, there being relative rotation between the cam ring and the gearing, and the inclination of said ring being adjustable so that the rate at which the rollers are driven can be varied within limits, for the purposes herein specified.

THOMAS CHARLES BROMLEY.
ARTHUR SHORTLAND.
